UNITED STATES PATENT OFFICE.

RAY E. ACRE, OF CHICAGO, ILLINOIS.

DESIGN FOR A GAS-ENGINE CYLINDER AND CASING.

45,218.

Specification for Design.

Patented Feb. 10, 1914.

Application filed November 19, 1913. Serial No. 801,999. Term of patent 7 years.

To all whom it may concern:

Be it known that I, RAY E. ACRE, a citizen of the United States, residing at Chicago, in the county of Cook and State of Illinois, have invented a new, original, and ornamental Design for a Gas-Engine Cylinder and Casing, of which the following is a specification, reference being had to the accompanying drawing, forming part thereof.

The drawing shows the design in perspective.

I claim:

The ornamental design for a gas engine cylinder and casing as shown.

In witness whereof, I have hereunto subscribed my name in the presence of two witnesses this 12 day of November 1913.

RAY E. ACRE.
